HILAND R. FARNSWORTH, OF SANDUSKY, OHIO, ASSIGNOR TO THE PAPER & TEXTILE MACHINERY CO., OF SANDUSKY, OHIO.

BOX SUSPENSION FOR SUCTION ROLLS.

Application filed January 11, 1928. Serial No. 245,961.

The present invention relates to suction rolls for paper making machines and more particularly to the box suspension of such rolls.

5 The more general practice in the use of these rolls has been and is to drive them by direct intermeshing gears, one gear being fixed to the shell at or near one end. In some mills, of recent years, there has been 10 a desire to use a gearless drive, most generally in the form of a drive shaft coupled directly to one end of the shell and being driven in well known manner from any suitable source of power. The main object of the 15 present invention is to provide a box suspension equally adapted for use with either type of roll-gear driven or gearless driven.

In order to more clearly disclose the construction, operation, and use of the invention, reference should be had to the accompanying drawings forming part of the present application. Throughout the several figures of the drawings like reference characters designate the same parts in the several 25 views.

In the drawings:—

Fig. 1 is a central, vertical, longitudinal cross section of the invention.

Fig. 2 is a like view of the box unit, removed from the shell.

Fig. 3 is a left hand end view of Fig. 1, on line 3—3, looking in direction of the arrows and with bearing box and cradle omitted;

Fig. 4 is a vertical cross section on line 35 4—4 of Fig. 1, looking in the direction of the arrows.

Fig. 5 is a cross section on line 5—5 of Fig. 1, looking in the direction of the arrows,

40 Fig. 6 is a similar cross section on line 6—6 of Fig. 1, and

Fig. 7 is a fragmentary cross sectional view on line 7—7 of Fig. 1, with suction box removed.

45 In the drawings, the openings of the suction box have been shown as directed vertically upward whereas, as a matter of fact they are, in practice directed radially, at a considerable angle to the vertical. This of course, does not alter the construction and actually any position around the entire circumference is within the limits of possibilities.

I will first deal with a construction of

roll in which the drive is direct-gearless 55 driven. I have devised a particular construction of shell for this purpose. In this construction the perforated shell 1 of usual and well known construction carries at one end a trunnion head 2 provided with a journal 3 extending outwardly therefrom and of considerably reduced diameter relatively to said head. The journal 3 is seated in an anti-friction bearing carried by a suitable standard at that end of the roll. In order to drive 60 the roll direct from the power element a suitable stub shaft 4 is keyed or otherwise fixed to the journal 3 and is driven from the power element by any well known transmission shaft 5, through a flexible coupling 6, the 65 flexible coupling being used for a purpose to be later disclosed. Preferably, the trunnion head 2 is of such diameter as to just snugly fit within the corresponding shell end and is provided with an attaching flange 2' overlying the end of the shell and through which 70 fastening bolts are passed and threaded into the shell end.

At the opposite end, the shell is supported on roller bearings 7 journaled in a cradle 80 or yoke 8 which is suitably housed in a standard 9.

The trunnion head 2 is cored out centrally and properly machined to provide an inner wall parallel with the wall which fits within 85 and receives the end of the shell and an adjoining annular radial face, the two forming an L in cross section. The inner diameter of this cored-out space is, of course, considerably less than the inner diameter of the 90 shell. Within the chamber thus formed and seated on such inner wall, is an annular bearing carrier 10 substantially L shaped in radial cross section. When in operative position, as in Fig. 1, the radially directed portion of the carrier is the innermost portion, the other member being directed toward the outer end of the shell. On reference to Fig. 1 it will be seen that the radial thickness of 95 this circumferential wall of the ring is considerably less than the radial width of the inner annular face of the cored out or chambered section of the head 2. In order to hold the carrier in its proper operative position, hook bolts 11 of L or other suitable 100 construction are provided. These bolts are slipped through elongated slots or eyes 12 105 suitably formed through the head, so that

the shanks of the bolts lie in grooves or channels in the longitudinal wall of the L shaped bearing carrier seat, the short arms or branches of the bolts overlying and engaging the radial face of the carrier. Nuts turned upon the outer ends of the bolts draw the carrier snugly into position. Seated in the carrier on the inner face of the longitudinal wall is an anti-friction bearing unit comprising the bearings themselves with inner and outer races. The outer race is of very slightly greater width than that of the longitudinal wall of the carrier in which it is supported. Thus when the bolts 11 are drawn up and the carrier in operative position, the ring edge will not quite engage the annular face of the head 2, and the adjacent edge of the outer race of the bearing will be pinched or become bound against the annular face of the head, so that the head 2, carrier 10, and outer bearing race will travel as a unit. Thus, it will be noticed that the outer race of the bearing is held against longitudinal movement, in either direction and, at the same time bound to the head 2 to rotate therewith.

Within the central opening of the carrier is freely mounted a hollow block 12. This block is seated on the inner race of the bearing and extends inwardly slightly beyond the radial wall of the bearing carrier.

The inner race, lying on the block 12, is held against longitudinal movement in one direction by the radial flange of the bearing carrier, as will be clear. Similar movement in the opposite direction is prevented by the headed screws 13 which are threaded into the edge of the block in such manner that their heads overlap and engage the adjacent edge of the inner race, as will be clear on reference to Fig. 7. In order to prevent possible rotation of the inner race, a small plate 14 in the form of a washer is used. This plate is fitted on the shank or stem of one of the screws and is adapted to be seated in aligned notches, grooves or recesses in the adjacent radial faces of block 12 and the inner race. When so seated and held by the head of its screw, the washer locks the block and inner race together against relative rotation, as will be clear on reference to Fig. 7. The bearing carrier, on the other hand, travels with the head 2. As previously set forth, its clamping action compels the outer race to travel with the head. To avoid undue wear between the travelling carrier and the relatively stationary inner race, the radial branch of the carrier is sufficiently recessed or cut away adjacent the corresponding radial wall of the inner race to leave a very slight space therebetween. Thus, the outer race travels freely with the head 2 while the inner race remains stationary or fixed. The details of construction of these several elements may

be varied in many ways, as will be obvious, and it is not intended to limit this case exactly to the construction disclosed.

Extending upwardly from the lower part of the block 12 and projecting both inwardly and laterally are wings, plates, or webs 15 which are bolted, riveted or otherwise suitably secured to the under surfaces of the inner ends of the treads of a pair of supporting rails 16. The opposite ends of these rails are made fast to the lower head section 17, at the opposite end of the shell. They may be bolted into the lateral webs either direct or by being provided with small extension plates 18 which are bolted or otherwise rigidly secured to such members, as indicated in Fig. 3.

Lower section 17, with its corresponding upper section 19 constitute a complete head. Preferably these head sections have coincident lateral webs which have a mortise and tenon fit or assembly, as in Fig. 3 and are held in such assembled relation by nut and bolt or other suitable connections. When so assembled, in the preferred construction, the complete head is of substantially circular outline. This completed head is held in operative position in the apparatus by an enclosing two part collar the lower part of which may be formed as part of the standard 90 12, the upper part being clamped thereto in any usual and well known manner. It is not thought necessary to show the clamping means of the collar or the details of its two-part construction, as it would add nothing to a full understanding of the invention, and is well understood.

From the above, it will be evident that the block 12, lower head section 17 and connecting rails 16 may be bodily withdrawn as a unit from the shell. It is only necessary to disconnect the two parts of the collar and withdraw the head, rails and block together. As a matter of convenience, the top section 95 19 is first disconnected and removed. It is assumed, of course, that the suction box is not yet in position and that the piping at that end has been previously removed.

The rails 16 are primarily for the placing and removal of a suction box 20 having the usual connection to a vacuum pump as in well known practice and being open to a limited arc of the shell, all as is well understood. To facilitate travel of the box on the rails, small wheels or rollers 21 are provided, journalled on suitable shafts or axles 22 carried by the box. Preferably, as shown in Fig. 1, there are two pairs of such rollers—one near each end of the box. This is particularly advisable, of course, with the larger sizes and longer boxes. On the inner end of the box the rollers are carried in the preferred construction, in a separate bracket 23, cast or otherwise formed and securely attached to the underside of the box in any 100 110 120 130

suitable manner. On reference to Fig. 1, it will be seen that the bracket 23 is formed with an extension 24 which, when the box is in operative position, projects within block 12. The free end of this casting is formed as a pair of parallel ears or plates 25 between which is pivotally mounted the upper end of a short link lever 26. The lower end of this lever is similarly mounted in a cross head 27 to which are connected the inner ends of a pair of rods 28, the opposite ends of which are slidably mounted in lugs 29 carried by the under face of the box. For adjustment purposes, the ends of these rods are threaded. Nuts 30 threaded thereon form the outer ends, by engagement with the outer faces of the lugs, limit the inward longitudinal travel of the rods. Travel in the opposite direction is yieldingly limited by a spring 31 disposed about each rod and confined between the inner wall of the respective lug and a nut 32 on the rod. By moving the nut 32 toward the lug the spring pressure will be correspondingly increased. And, as the pressure is increased, the longitudinal movement of the corresponding rod 28, in the outward or inoperative direction will be correspondingly resisted or decreased. Obviously, with the springs 31 under compression, as the nuts 30 are loosened (moved to the left) the rods 28 will be correspondingly moved toward the right—Figs 1 and 2. Likewise, by tightening the nuts 30 the rods 28 will be drawn in the opposite direction regardless of the spring pressure, until, of course, the spring has been put under such compression as to become inoperative as a spring.

On reference to Figs. 1 and 2 it will be evident that movement of rods 28 toward the right will extend the link 26 or move it to a position more nearly at right angles or perpendicular to said rods, while movement in the opposite direction will act reversely. Likewise, it is obvious that if the rods 28 are confined to such longitudinal movement, the link 26 as it moves toward the right angle position must, necessarily, force the box farther from the rods 28. It is equally clear that as the link 26 moves in the opposite direction, the box will approach the rods. This applies, of course, only to that particular end of the box, as there are no similar connections or lever action at the opposite end. Instead, such opposite end, as will later appear, is yieldingly maintained in operative position by an adjustable spring acting directly thereon. Here, as at the end carrying link 26 adjustment effecting compression of the spring, tends to permit similar corresponding movement of that end of the box, as will later appear.

On reference to Figs. 1 and 7 it will be noticed that the head at the left comprising upper and lower sections 17 and 19, respectively, is entirely independent of and separate from the shell. It is so positioned and mounted as to receive and support one end of the suction box—preferably, that end to which the suction connections are attached or with which they cooperate. Thus, when the roll is completely assembled and the box in position it will be supported, at its opposite ends, respectively, by the block 12 and heads 17 and 19. On reference to Fig. 3 it will be seen that the two head sections 17 and 19 have parallel spaced webs 33 and that these webs are so disposed in the respective head sections that, when assembled, the webs of one section will be aligned with and form continuations of the webs of the other section. It will also be seen that there is a cross web 34 in the section 17, such cross web connecting the parallel webs and forming therewith a U which extends substantially completely across the complete assembled head. The cross web is provided with a central notch for ready insertion of the shank of the rod or bolt 36, hereinafter described. Along the inner walls or faces of the parallel branches of this U are formed or secured suitable guides or ways 35 adapted to slidably receive and guide one end of the suction box 20. Through the connecting web 34 is slidably mounted a yieldingly adjustable supporting element, preferably, in the form of a rod or bolt 36. In the construction shown and which is that preferred, the upper end of the element is headed and adapted to be removably slipped into or inserted in a correspondingly formed groove, slot, or way made by providing the upper parts of the adjacent faces of the lugs 29 with oppositely directed inwardly extending parallel ribs or shoulders 37 spaced sufficiently from the adjacent wall of the suction box to accommodate the thickness of the head 38 of the element 36, the distance between the upper ends of the inner faces of the lugs being ample to freely allow the full width of said head in such relative sliding movement. The lower end of said element extends through and beyond the web 34, has free sliding movement relatively thereto, and, preferably, is threaded to receive an adjusting nut 39 which, in adjustment, is adapted to engage the adjacent face of the web 34. About the element 36 is disposed a yielding member, preferably, a coil spring 40 or similar suitable means capable of compression or expansion and of exerting its force upon the adjacent box end to maintain said box end in operative position, as in Figs. 1, 3, and 4. When in position, the ends of the spring engage, respectively, the cross web 34 and the ribs 37. By the nut 39, the force of the spring 40 may be regulated as desired, as will be well understood. As shown in the drawings, washers or the like 41 are interposed be-

tween the opposite ends of the spring and the web 34 and ribs 37, respectively, to provide adequate and accurate seating of the spring ends. While one form of a sliding 5 and detachable connection has been shown between element 36 and the suction box 20, it is clear that various other constructions may be resorted to—for instance T-headed or L-headed bolts with corresponding slots, 10 may be used. Likewise, though a detachable connection is disclosed, a fixed connection may be used and, of course, will operate to move the box in either direction, in the same manner.

15 The connection between the element 36 and suction box 20 in the preferred construction, is that shown in Fig. 3. That is a simple, efficient and economical construction. It will be seen that the ribs 37 will be positively engaged by the head 38 as the head is drawn down by the nut 39. Continued movement after such engagement, necessarily carries the box along with the rod 36 and away from the shell. Consequently, adjustment by unit 39 may be used to limit the movement of the box toward the shell. Limitation of movement in the opposite direction depends upon resistance of the yielding element 40. The movement will continue until the resistance of element 40 counteracts or overcomes the force acting against it, or until the yielding element ceases to yield and acts as a positive stop—when a coil spring is used, this point would be reached when the various coils contact one with another, forming, practically a continuous metal cylinder about element 36 and extending from washer to washer.

The suction box 20 is provided with any 40 usual and well known detachable piping connection at one end and carries parallel spaced packing channels adapted to receive or seat packing strips which, when the box is in operative position engage the inner face 45 or wall of the shell and, together with the adjustable deckle heads, hereinafter more particularly disclosed, serve to accurately delimit the area of shell through which the vacuum within the box becomes effective, as 50 well be readily understood. The two channels, with their packing strips thus disposed provide a shallow substantially U-shaped trough which communicates through one or more openings with the interior of 55 the box 20—see Figs. 2 and 4. Within the trough thus formed are slidably mounted suitable deckles or heads. Thus, when the box is assembled in the shell as in Fig. 1 the packing strips, deckles, shell and box 60 cooperate to form a complete chamber closed except from the atmosphere except through the shell arc perforations and open to the vacuum means only through the openings in the top of the box. The length of this 65 chamber is varied to accord with the width

of sheet which is to be made over the roll. For this purpose it is necessary to move one or the other, or both of the deckles longitudinally of the box. For this purpose, threaded deckle rods are provided, one for 70 each deckle and both operable from the same end of the roll—preferably the suction end, as shown in Fig. 1. In the construction illustrated and which is the preferred form of the apparatus, one rod is tubular and receives the other rod. The inner rod is extended to and threaded through the innermost deckle and, preferably, provided with a suitable stop at its extreme end to prevent the deckle being moved completely beyond 80 the ends of the packing. Its movement beyond a predetermined point in the opposite direction is stopped or prevented by the unthreaded portion of the deckle rod. At a point adjacent the inner end of the tubular 85 deckle rod the other or inner deckle rod is provided with a second stop collar adapted to engage the end of the tubular rod and prevent outward movement of such inner rod relatively to the tubular rod, movement 90 in the opposite direction being prevented by engagement of the operating hand wheel with a collar, sleeve, or like element formed on the outer end of the tubular rod. Movement of the outer rod in either longitudinal 95 direction is prevented by two spaced collars engaging opposite faces of a small flange or other suitable cooperating element or means either on the projecting end of the suction box or on some other relatively stationary 100 and rigid part of the machinery or apparatus. By the above construction, it will be readily seen that the effective length of the trough-shaped chamber may be quickly and accurately adjusted to any one of a wide 105 range of varying widths of sheet. An important feature of the deckle adjustment here disclosed is that the operation may be carried out at any and all times, regardless of whether or not the roll is running. For 110 this purpose, the end of the shell opposite head 2—the suction end usually—is left entirely open so that there is ample space between the suction box end and shell end during the entire rotation of the shell, as will 115 appear on reference to Fig. 1.

On reference to Figs. 1 and 2 it will be clear that the distance from the top of ears 24 to the bottom of face of yoke 27 when the link 26 is fully extended and substantially 120 at right angles to the yoke 27 is substantially equal to the vertical distance between the opposite inner walls of the block 12. Consequently, in assembling the box unit in operative position within the shell it is advisable to partially contract said elements to reduce this distance so that the yoke and ears may be slipped easily into place within the block. To more readily facilitate assembling, the free or innermost edge of the 125 130

yoke is slightly beveled or inclined, as at 42 so that should there, otherwise, be direct contact between such edge and the corresponding radial face of block 12 there will be no damaging shock but, instead, the yoke and its connected parts will simply ride up and onto the inner lower face of the block 12, as will be evident. An antifriction bearing or other element could be substituted.

5 When it is desired to assemble the roll, the bearing is first seated in its carrier, the carrier is then seated on block 12, the headed bolts 13 are then turned up, washer 14 being properly seated, and block 12 is then secured 10 to the ends of the rails 16. The opposite ends of the rails are secured to the lower head section 17, as previously set forth, thus making a single structural unit—the rail unit. It is assumed that the head 2 has been 15 previously secured in the corresponding end of the shell and that the shell, thus assembled, has been mounted, at its opposite ends, in the bearings provided. It is understood, of course, that for assembly purposes, the 20 upper or removable collar section—the clamping section—of the collar which encloses and holds the two part head 17—19, is omitted during the first steps of the assembly. The box 20, with attached parts 25 is now travelled along the rails 16 from the head section 17 toward block 12 until the ears 24 and yoke 27 extend well into or through said block, as in Fig. 1. It will be noticed that link 26 is in its extended position relatively to Fig. 2, so that the box end 30 and yoke 27 are, relatively, farther apart so that the packing strips would contact with the shell wall, if the roll were completely assembled. When the box has 35 reached the limit of its travel toward block 12 the rod 36 is slipped into position with spring 40 in extended condition. Before the box is traveled along rails toward block 12, it is, of course, necessary to compress springs 40 by the units 30 to draw the yoke 27 sufficiently close to the ears 24 to permit the two to pass into the opening in block 12. And, at the opposite end, the box must be drawn toward the web 34 by bolt 36 and nut 39 50 against the force of spring 40 until that end of the box will not bind against the inner shell surface as combined box and rail units are inserted as one element. Such being the case, the next step is to insert the locking bolts 11 through the slots 12 so that their shanks or stems will lie in the grooves in the longitudinal annular wall in head 2, with their locking ends turned to inoperative position and completely out of the path of the 55 bearing carrier 10 during the inserting movement of the rails and attached parts.

Now invert the combined unit, so that the rails 16 will lie above the box and use the packing strips as skids to ride on the lower

inner face of the shell and slide inwardly 65 until the bearing carrier is accurately seated in head 2. When so seated, turn the locking bolts to operative position and tighten, to clamp the carrier in position. The parts are so proportioned, of course, that when the 70 box unit and rail unit are thus combined and slid inwardly of the shell the bearing carrier and its connected parts will quickly and accurately centre and seat in the head 2. After the parts have been thus assembled, 75 the combined unit may be rotated to bring the box above the rails again, as in Fig. 1. When the combined unit has been turned back to this position, the nuts 30 and 39 are operated to move the box, against the counteracting force of the yielding elements, until there is the lightest practicable operable contact between the box packings and inner shell face. At this point the adjustment may be definitely fixed by suitable co-operating lock nuts. On reference to Figs. 1—3 it will be noticed that the nuts 30 and 39 provide efficient positive stops to outward movement of the box beyond a predetermined point, thus definitely preventing any undue binding between shell and box, due to greater pressure on outside of box. On the other hand, the springs do permit inward movement away from shell to accommodate 80 passage of small foreign matter between shell and packing in operation. The next step is to slip head section 19 into place on the box end, fasten it to section 17 and then securely clamp the assembled head to the standard by the removable upper collar section. The roll is now completely assembled 85 and ready to be connected to any suitable source of vacuum.

Referring to Fig. 4 it will be noticed that when the roll has been completely assembled as above set forth and is ready for operation, the rolls 21 of box 20 do not actually rest on the rails 16 but, instead, are spaced somewhat upwardly therefrom.

Assume, now that it is intended to remove the box unit only. First, remove the bolt 36 with its spring 40 to permit that end of the box to drop away from the shell and the corresponding rollers 21 to seat on the supporting rails 16. Then retract the opposite end of the box until the rollers at that end are similarly seated. Now, remove the clamp section of the collar and the head section 19 and roll out the box unit complete, travelling the rollers 21 along the supporting rails 16. It may then be repaired, parts altered or renewed or any work done on it that may be desired and again returned to its operative position within the shell.

Again, assume that repairs to the block 12, the bearing carrier 10, rails 16 or other parts entering into the structure of the combined units but not in the box unit, become

necessary. They must be removed for repair, etc. To accomplish this it is only necessary to invert the box and rails and draw out the combined units, on the box packing as 5 skids, reversing the operation of inserting. Necessarily, as soon as the box has been inverted, the locking bolts are loosened and then turned to clear the bearing carrier so that it may have unobstructed travel with 10 the block 12, etc. Thus, it is possible to easily and quickly remove either the box unit, alone, or the entire operable mechanism from the inside of the shell, leaving only the shell 1 and trunion head 2. These, in turn, 15 may be readily separated by simple unbolting so that either of them may be repaired, renewed, altered, replaced, etc.

It is necessary, of course, to adequately lubricate all contacting moving parts. Thus 20 the contacting surfaces of block 12, carrier 10 and the bearing and bearing races must be lubricated. This lubricant, even with suitable drainage passages through head 2 will, nevertheless, tend to accumulate in the 25 chambered part of head 2 and to be picked up by rotation of the roll and work through the block 12 to the inside of the shell and thence pass to the wire. The damage done by such leakage is well understood. To 30 avoid this a dam or wall is provided in the form of a plate 50. It is in the form of a cap extending completely over the end of the block so that no lubricant can get into the openings through the block. Its edge is 35 secured to the corresponding edge of the block by the headed screws 18, as will be clear on reference to Fig. 7. In the particular construction illustrated, this plate is shown as dished or concavo-convex with a 40 flat peripheral attaching flange. This is due to the fact that the ears 24 extend slightly beyond the block 12 into the cored out portion of head 2. In cases in which the ears lie entirely within the block or, at least, do not 45 project beyond, the plate, obviously, may be flat. In fact, if desired, in such cases, the block 12 may be formed integrally with the plate, in any suitable and well known manner.

50 It is hardly necessary to state that the suction box may be set and secured at any desired angle, circumferentially of the shell by simply turning the head 17-19 and connected parts and then clamping them in adjusted position by the collar, as will be readily understood.

Generally speaking, the invention comprises a suction box suspension means whereby the box may be moved laterally through 60 mechanism controllable from one end of the roll or a point in the neighborhood of one end, the term lateral meaning in a direction approximately at right angles to the length or greatest dimension of the box and, therefore, when the box is in operative position

within the shell, in a generally radial direction relatively to the shell, all adjustments of the controlling mechanism being at or close to one end of the shell and very readily accessible. Together with this main feature 70 of the invention are combined and associated means for limiting such lateral movement in one direction, and means for yieldingly resisting movement in the opposite direction. A further feature of the invention 75 comprises a readily removable unitary box construction and box actuating means, associated with a unitary construction adapted to support the box ends and provide guiding and supporting rails for the insertion of 80 the box.

An important consideration in the present invention is the simplicity of the construction whereby the distant or innermost box end is operable and its operation made adjustable from and at the near end, access to such inner end for corresponding adjustments being completely barred by the head 2. 85

It will be understood that one form only of the invention has been disclosed in the 90 drawings and that such showing is to be considered illustrative merely and in no degree limiting applicant to the construction so illustrated. Many changes may be made in the construction arrangement and disposition of the several parts of the invention and in their various details within the scope and intent of the appended claims without departing from the field of the invention and it is meant to include all such within this application. 95 100

Having described my invention, what I claim and desire to protect by Letters Patent is:—

1. In combination with a suction box for 105 suction rolls, means for moving said box laterally and means for operating the same from a point remote therefrom.

2. In combination with a suction box for 110 suction rolls, means carried by said box and adapted to move said box laterally, and means for operating the same from a point remote therefrom.

3. In combination with a suction box for 115 suction rolls, means carried by the opposite ends of said box and adapted to actuate said box laterally, and means in the neighborhood of one end of said box for operating all said actuating means.

4. In combination with a suction box for 120 suction rolls means carried by said box and adapted to move said box laterally, means for operating the same from a point remote therefrom and means remote from said actuating means for regulating its operation. 125

5. A suction roll comprising a perforate shell, a suction box extending longitudinally within said shell from end to end, means carried by one end of said box and adapted to actuate the same laterally, and means for 130

- operating said actuating means from a point adjacent the opposite end of said box.
6. A suction roll comprising a perforate shell, a suction box extending longitudinally within said shell from end to end, means carried by the opposite ends of said box and adapted to actuate said box laterally, and separate means adjacent one end of said box for operating both said actuating means.
10. 7. A suction roll comprising a perforate shell, a suction box extending longitudinally within said shell from end to end, means carried by the opposite ends of said box and adapted to actuate said box laterally, separate means adjacent one end of said box for operating both said actuating means, and means for adjusting said operating means.
8. A suction roll comprising a shell having one closed end, a suction box extending longitudinally within said shell from end to end, means carried by the suction box end adjacent the closed end of the shell and adapted to actuate the box laterally, operating means therefore connected thereto and extending to a point adjacent the opposite end of said suction box, and means for actuating the opposite end of said box laterally.
9. A suction roll comprising a shell, a suction box extending longitudinally within said shell from end to end, means carried by one end of the suction box and adapted to actuate that end laterally and spring actuated rods connected to and adapted to operate said actuating means and extending approximately to the opposite end of the box.
10. A suction roll comprising a shell, a suction box extending longitudinally within said shell from end to end, a link carried by one end of said box and adapted to actuate said box laterally, a yoke and rods connected to said link, said rods being extended to a point adjacent the opposite end of said box, yielding means carried by said rods and adapted to operate the same, and means for adjusting said yielding means.
11. A suction roll comprising a shell, a suction box extending longitudinally within said shell from end to end, means carried by one end of said box for actuating said box laterally, a link carried by the opposite end of said box, and adapted to actuate said box laterally, a yoke connected to said link, rods connected to said yoke and extended to a point adjacent the opposite end of said box, yielding means for operating said rods and yoke, and means for adjusting said yielding means.
12. A suction box unit for use in suction rolls comprising, a suction box, a laterally acting link carried by one end of said box, a pair of rods extending longitudinally of said box and supported at the opposite end of said box, means for operating said rods, connections between said rods and link, and means for adjusting said rod operating means.
13. In combination in a suction roll a revolute shell, a block mounted in said shell and stationary relatively thereto, a suction box mounted at one end in said block, means carried by said suction box end and adapted to actuate the same laterally, operating means connected thereto and extending to a point remote therefrom and adjacent the opposite end of said box, and means for adjusting said operating means.
14. In combination in a suction roll, a revolute shell, a pair of guide rails therein, a bottom head section carried at one end of said rails and a block carried at the opposite end, a suction box adapted to be travelled along said rails to operative position, a link carried by one end of said box and adapted to actuate the same laterally, a yoke adapted to rest in sliding contact on said block, connections between said yoke and said link, rods connected to said yoke and extending to a point adjacent the opposite end of said box, and means adjacent said opposite end for operating said rods.
15. In combination in a suction roll, a revolute shell, suction box guide rails therein, a head section connected to said rails at one end, a block secured to said rails at the opposite end, a bearing carried by said block, a bearing carrier engaging and partially enclosing said bearing and seated in said head, and means for detachably locking said carrier and associated parts to said head.
16. In combination in a suction roll, a revolute shell, suction box guide rails therein, a head section connected to said rails at one end, a block secured to said rails at the opposite end, a bearing carried by said block, a bearing carrier engaging and partially enclosing said bearing and seated in said head and means operable from the outside of said head for detachably locking said carrier and associated parts to said head.
17. In combination in a suction roll, a revolute shell, a trunnion head secured to and closing one end and provided with a journal of considerably reduced diameter relatively to the diameter of the shell, said head being provided with an annular seat, a bearing carrier adapted to be seated thereon, a bearing seated within said carrier, a block seated on said bearing and connected thereto, and means for detachably connecting said bearing carrier and associated parts to said head.
18. In combination in a suction roll, a revolute shell, a trunnion head secured to and closing one end and provided with a journal of considerably reduced diameter relatively to the diameter of the shell, said head being provided with an annular seat,

a bearing carrier adapted to be seated thereon, a bearing seated within said carrier, a block seated on said bearing and connected thereto, and means operable entirely from outside said roll for detachably connecting said bearing carrier and associated parts to said head.

19. In combination in a suction roll, a revoluble shell, a trunnion head secured to and closing one end and provided with a journal of considerably reduced diameter relatively to the diameter of the shell, said head being provided with an annular seat, a bearing carrier adapted to be seated thereon, a bearing seated within said carrier, a block seated on said bearing and connected thereto, means for detachably connecting said bearing carrier and associated parts to said head, and a lower head section connected to the opposite ends of said guide rails.

20. In combination in a suction roll, a revoluble shell, a head adapted to close one end and a chamber formed in its inner face, an anti-friction bearing mounted in said chamber, a suction box supporting block mounted on said bearing, and means for preventing passage of a lubricant from said chamber through said block.

30 21. A suction roll comprising a shell, a suction box extending longitudinally within said shell from end to end, means carried by the suction box adjacent one end of the shell and adapted to actuate the box laterally, operating means therefor connected thereto and extending to a point adjacent the opposite end of said suction box, and means for actuating the opposite end of said box laterally.

40 22. A suction roll comprising a shell, a suction box extending longitudinally within said shell from end to end, flexible means carried by the suction box adjacent one end of the shell and adapted to actuate the box laterally, operating means therefor connected thereto and extending to a point adjacent the opposite end of said suction box, and means for actuating the opposite end of said box laterally.

50 23. A suction roll comprising a shell, a suction box extending longitudinally within said shell from end to end, flexible means pivotally carried by the suction box adjacent one end of the shell and adapted to actuate the box laterally, operating means therefor connected thereto and extending to a point adjacent the opposite end of said suction box, and means for actuating the opposite end of said box laterally.

60 24. A suction roll comprising a shell, a suction box extending longitudinally within said shell from end to end, a lever pivotally connected to said box and adapted to actuate the box laterally, operating means for

said lever and extending to a point adjacent the opposite end of said suction box and means for actuating the opposite end of said box laterally.

25. A suction box unit for use in suction rolls comprising, a suction box, a member movable longitudinally of said box, a laterally acting device connected to said box and to said longitudinally movable member, means for operating said longitudinally movable member, and means for adjusting said operating means.

26. In combination in a suction roll, a revoluble shell, suction box guide rails removably mounted therein, a block carried by said rails, a bearing carrier carried by and removable with said block and a bearing carried by said carrier.

27. In combination in a suction roll, a revoluble shell, suction box guide rails removably mounted therein, a block carried by said rails, a bearing carrier carried by and removable with said block, a suction box supported in said block, and a bearing carried by said carrier.

28. In combination in a suction roll, a revoluble shell, suction box guide rails removably mounted therein, a block carried by said rails, a bearing carrier carried by and removable with said block, a suction box supported in said block and movable laterally thereof, and a bearing carried by said carrier.

29. In combination in a suction roll, a revoluble shell, suction box guide rails removably mounted therein, a block carried by said rails, a bearing carrier carried by and removable with said block, a suction box supported in said block and movable laterally thereof, means for moving said box laterally, and a bearing carried by said carrier.

30. In combination in a suction roll, a revoluble shell, suction box guide rails removably mounted therein, a block carried by said rails, a bearing carrier carried by and removable with said block, a suction box supported in said block and movable laterally thereof, means engaging said block and said box to move said box laterally, and a bearing carried by said carrier.

31. In a combination with a suction box, means exterior to said suction box for moving said box bodily laterally and means for operating the same, and means for actuating said operating means from a point remote therefrom.

32. In combination with a suction box, means exterior to said suction box for moving said box laterally, said means acting against the suction box and against a part separate and independent of said box, and means for operating the moving means from a point remote therefrom.

33. In combination with a suction box for

suction rolls, means for moving an end of said box laterally and means for operating the same from a point remote therefrom.

34. In combination with a suction box for suction rolls, means carried by said suction box for moving an end of said box laterally, and means for operating the same from a point remote therefrom.

35. In combination with a suction box for suction rolls, means carried by one end of 10 said suction box for moving an end of said box laterally, and means for operating the same from a point remote therefrom.

Signed at Sandusky, county of Erie, State of Ohio, this 9th day of January, 1928.

HILAND R. FARNSWORTH.
